UNITED STATES PATENT OFFICE.

HERBERT J. KRATZER, OF ST. LOUIS, MISSOURI.

ROAD-BED.

1,301,064.

Specification of Letters Patent. Patented Apr. 15, 1919.

Application filed December 11, 1916. Serial No. 136,169.

To all whom it may concern:

Be it known that I, HERBERT J. KRATZER, a citizen of the United States of America, and a resident of the city of St. Louis and 5 State of Missouri, have invented certain new and useful Improvements in Road-Beds for Railway-Rails, of which the following is a specification.

The primary object of this invention is to 10 provide an improved road bed for the laying of railway rails which in itself will be practically permanent, in which provision is made whereby the rails can be removed without destroying the road bed.

15 Another object is to provide an improved manner of securing rails to this improved road bed.

A further object is to provide an improved road bed which in addition to being 20 permanent, improved means are provided whereby, when the rails are mounted in position, the usual truing or leveling of the rails is done away with.

A still further object of this invention is 25 to provide an improved construction of road bed in which the rails will be resiliently mounted in the road bed, thereby providing a noiseless supporting structure.

Other and further objects will appear in 30 the specification and be specifically pointed out in the appended claims, reference being had to the accompanying drawings exemplifying the invention, and in which,

Figure 1 is a fragmentary plan view of a 35 portion of this improved road bed, showing the rail portions mounted thereon.

Fig. 2 is an enlarged transverse section of Fig. 1.

Referring to the drawings, 1 designates a 40 road bed, preferably constructed of concrete, or the same can be made of any self hardening plastic material, said road bed being reinforced by the bars 2 and 3.

Formed in said road bed are a pair of 45 longitudinally arranged grooves 4, each of said grooves having expanded side walls 5 formed adjacent the bottom thereof, and outwardly flaring walls 6 formed adjacent the top thereof, the bottom 7 of each of said

grooves 4 and said expanded side walls 5 50 being lined by a metallic channel member 8.

In the construction of this improved road bed, it is preferable to first elevate the channel members 8 to the desired level, said channel members being several feet in 55 length. Forms are then mounted on each of the channel members relative to the making of the upper portion of each groove. The body of concrete is then mounted under and around each of the channel members and 60 around the forms, said body of concrete being reinforced in any desired manner.

When the forms, not shown, are removed, a pair of grooves as described is the result, 65 the channel members 8 being left embedded in the body of concrete. The grooves 4 are then ready for the reception of the rails and their supporting structure, in which wooden blocks 9, which are the approximate length 70 of the width of the channel members 8, are first laid in an abutting relation in each of said channel members, said blocks being first treated with a preservative, such as creosote oil.

Tar oil is then poured on the blocks 9 to serve as a filling around and between the 75 blocks and also as a further preventive against deterioration. These blocks 9 are of a thickness so that the upper surfaces adjacent the ends thereof will engage against the inwardly extending flanges 10 of the channel members 8. Rails 11 are then 80 mounted in each groove 4 on the laid blocks 9, said rails being gaged relative to proper wheel tread, and the rail securing lag screws 12 are engaged into the blocks 9 thereby 85 holding the rails in proper position. A body of sand 13 is then laid over each base of each rail and on top of the blocks 9. Filling bricks such as 14 and 15 having inclined surfaces 17 and 18, respectively, are 90 then mounted in place against the rails and on top of the body of sand, the inclined faces of said bricks bearing against the outwardly flaring walls 6 of the grooves 4. A wearing surface 16, such as asphaltum is then mounted 95 on the concrete body between the inner rows of bricks 14, and wearing surfaces such as 19 are filled in against the outside rows

of brick 15. This completes the construction of this improved road bed, and on account of the fact that the rails are mounted on the wooden blocks 9, enough resiliency 5 will be provided to the rails so as to provide for the yielding strain that will be given to the rails from the rolling stock passing thereover. Furthermore, said wooden blocks will serve as deadeners to the sound on account of the fact that the jarring of the 10 rolling stock when applied to the rails will be transferred to the wooden blocks, and since said blocks are resilient, said blocks will serve somewhat as shock absorbers to 15 the jarring strains.

Owing to the fact that it is found that oil will commence deterioration of concrete, attention is called to the channel members 8 which will contain the tar oil relative to the 20 blocks 9, which will prevent the oil from coming in contact with the concrete road bed.

The body of sand 13 which is filled in over the blocks 9 after the rails have been 25 mounted thereon will serve as an insulation to said blocks 9 against water seeping into the channel members 8 and around the blocks, thereby preventing dampness and subsequent deterioration to the blocks. The 30 bricks 14 and 15 will also assist preventing water from getting to the blocks 9, although said bricks are primarily intended to serve as good wearing surfaces adjacent the rails, and also to protect the upper edges of the 35 walls of the grooves 4.

Attention is also called to the inwardly extending flanges 10 of the channel members 8 which will serve as a reinforcement to the concrete walls of the groove against 40 downward strains, and at the same time serving as a reinforcement against upward strains during the undulating movements of the rails relative to the resiliency of the blocks 9 while rolling stock is passing over 45 said rails.

It is known that the life of street railway rails is very short on account of the traffic thereover being heavy, and in the present day methods of removing worn out rails, 50 the whole roadbed is broken up. It is therefore the intent of this invention to provide a permanent road bed with pairs of rail seating grooves, in which the filling in or supporting elements or members relative to 55 the rails can be easily removed without destroying any part of the road bed, as all of the parts which are mounted in the grooves 4 of this improved road bed can easily be demounted and removed.

60 Furthermore the manner in which the rails are secured in the grooves provides means for the better securing of the rails to the road bed than heretofore, as the rails

are practically keyed or locked to the road bed on account of the engagement of the 65 wooden blocks 9 under the extending flanges 10 of the channel members 8.

After the removal of worn out rails from an improved road bed of this character, the 70 grooves 4 are found to be in the original condition in which they were made, and all that is necessary is a repetition of the mounting of the building or filling structure as afore related, and the rails will be found to have the desired elevation without any 75 additional adjustment or leveling of the wooden blocks 9.

What I claim is:

1. In roadbed construction, a longitudinally arranged groove formed in the roadbed being wider at the bottom than adjacent the top, a rail mounted in said groove, removable sectional rail supporting members mounted in said groove each having a rail base recess formed therein, said recesses of 85 said members being for the reception of the base of said rail.

2. A road bed having longitudinally arranged grooves formed therein, each of said grooves having opposing vertical walls, the 90 lower walls of each groove being wider apart than the upper walls, rails for said grooves of said road bed, and means for removably securing said rails in said grooves of said 95 road bed.

3. A road bed constructed of a body of concrete material, longitudinally arranged grooves formed in said concrete body each being enlarged at the bottom, resilient members mounted in said grooves, and rails secured to said resilient members, said resilient members and said rails adapted to be removed from said grooves without destroying said concrete body.

4. A road bed comprising a concrete body portion, a pair of longitudinally arranged grooves formed in said body portion, each of said grooves being wider at the bottom than adjacent the top thereof, a rail mounted in each of said grooves, and a removably mounted support located in each of said 105 grooves for supporting each of said rails.

5. A road bed comprising a concrete body portion, a pair of longitudinally arranged grooves formed in said body portion, each 110 of said grooves being wider at the bottom than adjacent the top thereof, a rail mounted in each of said grooves, a removably mounted support located in each of said grooves for supporting each of said rails, 115 and a removable filling material mounted on said supports in said grooves.

6. A road bed comprising a concrete body portion, a pair of longitudinally arranged grooves each being wider at the bottom than 120 at the top formed in said body portion, a 125

channel member located in each of said grooves, removable fibrous body portions located in each of said channel members, and rail sections mounted on said fibrous body portions of said channel members.

5 7. In roadbed construction, a rail bed comprised of self-hardening plastic material

having a longitudinal groove formed therein, which is wider at the bottom than adjacent the top, a rail mounted in said 10 groove, and a plurality of removably mounted fibrous supports for supporting said rail.

HERBERT J. KRATZER.
